John B. Garter

United States Patent Office.

JOHN B. CARTER, OF HARTSVILLE, INDIANA.

Letters Patent No. 94,183, dated August 31, 1869.

IMPROVEMENT IN BUTTONS OR STUDS.

The Schedule referred to in these Letters Patent and making part of the same.

To all whom it may concern:

Be it known that I, JOHN B. CARTER, of Harts-
ville, in the county of Bartholomew, and State of Indiana, have invented a new and useful Improvement in Buttons; and that the following is a full and correct description of the same, reference being had to the accompanying drawings, which are made a part of this specification.

My improved button is designed especially for fastening cuffs, collars, and cravats.

The principal peculiarity in the invention consists in forming the neck of the button to fit and fill the button-hole with which it is intended to be used, and with a conical head of approximately similar form, but slightly longer, the extremities of the head projecting slightly so as to form shoulders, over which the button-hole may be stretched, when the button is inserted, but which will prevent its accidental escape.

In the drawings—

Figure 1 is a perspective view of a cuff-button, illustrating my invention.

Figure 2 is a plan view of the same, showing also a section of the cuff.

Figure 3 is a perspective view of a collar-button, of similar construction.

Figure 4 is a plan view thereof, showing sections of the collar and shirt-band.

Similar letters of reference indicate corresponding parts in the several views.

The neck N of the button is made of elliptical form, and of a size to correspond with that which is usual in the button-holes of shirt-collars and cuffs.

The head H has, at its base, a form similar to that of the neck, but is of slightly greater size, and it converges to an apex, h, giving to the front of the button

a conoidal or wedge-like form, so that the button-hole may be readily drawn or stretched over it.

The longitudinal extremities of the head form shoulders or projections i i, which effectually secure the garment from escape or accidental displacement.

The cuff-button (figs. 1 and 2) is provided with a flange, F, to protect the wrist of the wearer, and requires no shank.

D D represent parts of the cuff.

The collar-button (figs. 3 and 4) is made with a shank, S, to receive and hold the neck-band of the shirt in customary manner.

B B represent the neck-band of the shirt;

C C, the collar-band; and

C' C', the flaps or front portions of the collar, which are turned over, and may conceal the extremities of the button.

My invention is of great utility in retaining the collar, cuff, or other garment, in the proper position in which it is adjusted, instead of leaving it free to shift and yield, as it does on the contracted neck of buttons in common use. Hence, my improvement not only promotes neatness and comfort in the dress, but greatly reduces the wear upon the button-hole.

Having thus described my invention,

What I claim, and desire to secure by Letters Patent, is—

As a new article of manufacture, the cuff or collar-button, constructed with an elongated neck, N, plates F S, one or both, convex or conical head H, and projecting shoulders i, in the manner and for the purposes specified.

Witnesses: JOHN B. CARTER.

OCTAVIUS KNIGHT,
J. GRINNELL.
